CLAIM

(30) **Foreign Application Priority Data**

May 12, 2009 (KR) 30-2009-0020233

The ornamental design for a spoiler wiper blade, as shown and described.

(51) **LOC (9) Cl.** **12-06**

DESCRIPTION

(52) **U.S. Cl.** **D12/219**

FIG. 1 is a perspective view of a spoiler wiper blade showing my new design;

(58) **Field of Classification Search** **D12/219-220;**

FIG. 2 is a front view thereof;

15/246, 247, 250.001, 250.4, 250.361, 250.19,
15/250.48, 250.03, 250.31–250.33, 250.351,
15/250.38, 250.201, 250.451, 250.458, 250.04,
15/250.07, 250.44

FIG. 3 is a rear view thereof;

See application file for complete search history.

FIG. 4 is an enlarged left side view thereof;

(56) **References Cited**

FIG. 5 is an enlarged right side view thereof;

U.S. PATENT DOCUMENTS

FIG. 6 is a top plan view thereof;

D442,537 S 5/2001 Kim

FIG. 7 is a bottom plan view thereof;

D443,245 S 6/2001 Kim

FIG. 8 is a perspective thereof;

6,539,576 B2 4/2003 Kim

FIG. 9 is a perspective view thereof; and

(Continued)

FIG. 10 is a perspective view thereof;

FOREIGN PATENT DOCUMENTS

FIG. 11 is an enlarged perspective view thereof; and,

CA 115235 10/2007

FIG. 12 is an enlarged perspective view thereof in an alternate position.

CA 119152 9/2008
